The ornamental design for the tent with pitched end panels, as shown and described.

DESCRIPTION

FIG. 1 is a right side elevational view of a tent with pitched end panels showing a first embodiment of my new design with an exemplary window shown in phantom, the left side being a mirror image thereof; FIG. 2 is a perspective view thereof, showing the window and a door in phantom;

FIG. 3 is a front elevational view thereof, the rear being a mirror image thereof;

FIG. 4 is a top plan view thereof;

FIG. 5 is a bottom plan view thereof;

FIG. 6 is a cross-sectional view taken along line 6—6 of FIG. 3 showing the curvature of the roof of the tent; and,

FIG. 7 is an end view of a tent with pitched end panels, showing a second embodiment of my new design.

The characteristic feature of the design resides in the provision of pitched end panels and a roof which is pitched in two directions which are generally perpendicular to each other.
